(57) **CLAIM**

The ornamental design for solar power unit, as shown and described.

DESCRIPTION

FIG. 1 is a perspective front view of a solar power unit showing my new design;

FIG. 2 is a perspective rear view thereof;

FIG. 3 is a front plan view thereof;

FIG. 4 is a back plan view thereof;

FIG. 5 is a top plan view thereof;

FIG. 6 is a bottom plan view thereof;

FIG. 7 is a right side view thereof; the left side view is a mirror image thereto; and,

FIG. 8 is a perspective front view thereof shown in use in an unclaimed environment.

The broken lines shown in FIGS. 1, 7 and 8 show unclaimed environment only and form no part of the claimed design.
